UNITED STATES PATENT OFFICE.

HENRY W. PARTON, OF YONKERS, NEW YORK, ASSIGNOR TO THE ALEXANDER SMITH & SONS CARPET COMPANY, OF SAME PLACE.

DESIGN FOR CARPET.

SPECIFICATION forming part of Design No. 25,904, dated August 4, 1896.

Application filed June 18, 1896. Serial No. 596,070. Term of patent 3½ years.

To all whom it may concern:

Be it known that I, HENRY W. PARTON, of Yonkers, county of Westchester, State of New York, have invented and produced a certain 5 new and original Design for Carpets, fully described and represented in the following specification and the accompanying drawing, forming a part of the same.

The design is intended to be worked into 10 or upon carpets or similar fabrics; and I do hereby declare that the drawing accompanying this specification conveys to any one skilled in the art of carpet weaving and manufacture a clear understanding of the same 15 and is sufficient to enable such person to use my invention.

The design is characterized by the flower-heads A on leafed stems B, bearing small flower-clusters C with the curved ornamentation D, having a checked or lace-like appearance and forming open or unornamented spaces on the ground E.

The design may be applied in a variety of colors or combination of colors.

What I claim as new, and desire to secure 25 by Letters Patent, is—

The design for carpets, substantially as shown and described.

In testimony whereof I have hereunto set my hand in the presence of two subscribing 30 witnesses.

HENRY W. PARTON.
